UNITED STATES PATENT OFFICE.

AUGUST R. LUSCHKA AND JOSEPH FOLK, OF LAPORTE, INDIANA, ASSIGNEES TO U. S. SLICING MACHINE COMPANY, OF LAPORTE, INDIANA, A CORPORATION OF INDIANA.

SLICING-MACHINE.

1,310,197.

Specification of Letters Patent. Patented July 15, 1919.

Application filed June 7, 1918. Serial No. 238,632.

To all whom it may concern:

Be it known that we, AUGUST R. LUSCHKA and JOSEPH FOLK, citizens of the United States, residing at Laporte, in the county of Laporte and State of Indiana, have invented certain new and useful Improvements in Slicing-Machines, of which the following is a specification.

This invention has for its object the provision of a machine of the class named which shall be of improved construction and operation.

The invention is exemplified in the combination and arrangement of parts shown in the accompanying drawings and described in the following specification, and it is more particularly pointed out in the appended claims.

In the drawings—

Fig. 1 is a side elevation of a slicing machine embodying one form of the present invention.

Fig. 2 is a bottom plan view of the machine shown in Fig. 1.

Fig. 3 is a side elevation of the base frame of the machine with the guard for the drive belt removed.

Fig. 4 is a view similar to Fig. 5 with the gear casing and cover for the motor removed, and with parts in section.

Fig. 5 is a vertical section substantially on line 5—5 of Fig. 2; and Fig. 6 is a horizontal section on line 6—6 of Fig. 1.

In Fig. 1 of the drawings, the base frame 10 of the slicing machine is shown as arranged upon a pedestal 11, and provided on its upper surface with a pair of guide rods or ways 12 and 13, upon which a reciprocating table 14 is mounted to slide in the usual way. A meat support 15 is carried by the table 14 and slides upon the table in a direction transverse to the direction of reciprocation of the table. The usual clamp 16 is provided for holding the meat in place, and the support 15 is fed transversely of the reciprocating table by a feed screw formed upon the shaft 17. The shaft 17 is given a slight rotary movement at each reciprocation of the table 14, by means of a ratchet wheel 18 actuated by a pawl 19 carried upon an arm 20, which is in turn operated by a rack segment 21 on a lever 22. The lever 22 is oscillated by means of a cam 23 journaled on the lower surface of

the table 14 and oscillated by a link 24 which connects the cam 23 with a pivot pin 25 secured to a pitman rod 26 by means of which the table 14 is reciprocated. A cam segment 27 may be shifted by a rod 28 and a lever 29 to regulate the amount of rotation of the ratchet wheel 18 for each operation of the pawl 19. The ratchet feed as described is shown and claimed in our co-pending application, Serial No. 222,802.

The pitman rod 26 for reciprocating the table 14 is operated by a crank 30 secured to an upright shaft 31 which extends through a bearing 32 projecting downwardly from the upper plate of the base frame 10, as shown best in Fig. 5. Secured to the lower end of the shaft 31 is a gear 33 which meshes with pinions 34, 35 and 36, as shown in Fig. 2. The pinion 34 is connected with a shaft journaled in a bearing 37 and arranged to drive the slicing knife 38 through a sprocket chain 39 in the usual manner. The pinion 35 is connected with a shaft 40 journaled in bearings 41 and 42 and carrying a fly wheel 43 which may be provided with a detachable handle 44 by means of which the machine may be driven by hand, when desired. The pinion 36 is connected with a shaft 45, as shown in Fig. 6, the shaft being journaled in a bearing 46 formed on a plate 47 secured to the outer face of the base frame so that the bearing 46 projects through an opening 48 in the wall of the base frame.

A spur gear 49 is rigidly secured to the outer end of the shaft 45 and meshes with a pinion 50 journaled on a stud shaft 51 rigidly carried by a boss 52 formed on the plate 47. The pinion 50 is secured to one end of a sleeve 53 which is journaled upon the stud shaft 51 and which carries at its outer end a pulley 54 held in place by a cotter pin 55. The gears 49 and 50 are enclosed in a casing 56 provided with an opening 57 through which the shaft 51 extends to carry the pulley 54 outside of the casing. A circular plate 58 is secured to the outer end of the casing 56 and forms a cover plate for the inner face of the pulley 54. A belt 59 passes around the pulley 54 and a guard 60 covers the belt 59 and pulley 54 and is held in place by a number of lag screws 61. The belt 59 is driven by a pulley 62 secured to a shaft 63 of a motor 64.

The motor 64 is inclosed in a cylindrical casing and is located within a circular opening in the base frame 10 formed by webs 65 projecting downwardly from the upper plate 5 of the base frame, as shown in Figs. 2, 5 and 6. The motor is held rigidly in position by a flexible strap 66 which passes beneath the central portion of the motor casing and has its ends attached to sockets 67 which 10 receive the threaded ends of lag screws 68 extending downwardly through openings in the upper plate of the base frame 10, as shown best in Fig. 5. By tightening the screws 68 the motor may be rigidly held in 15 place, but may be easily released and removed from the base of the machine by releasing the screws and drawing the motor forwardly from its circular seat. A casing 70 incloses the outer portion of the motor 20 64 and is provided with an opening 71 through which the shaft 63 extends and which is large enough to permit of the passage of the pulley 62 so that the casing 70 may be removed without detaching the pulley 62 from the motor shaft. The belt guard 60 incloses the pulley 62 and a portion of 25 the belt passing over the pulley. A socket 72 for an electrical connection 73 is mounted upon the outer face of the casing 70, and 30 electrical connection is made from the socket 72 through a switch 74 and cables 75 to the motor 64. It will be apparent that the motor 64 may be removed from its support without disturbing any of the electrical connections since the cover 70 and the motor 35 may both be detached from the frame of the machine and removed from the frame while still connected to one another by the cables 75. The belt guard 60, is, of course, re- 40 moved before removing the motor and cover 70. An idler pulley 76 is mounted to slide vertically in a slot 77 formed in the outer face of the gear casing 56 and may be clamped in various positions of adjustment 45 by a screw 78. The pulley 76 is for the purpose of adjusting the tension in the belt 59.

It should be noted that the mechanism of the power drive is completely inclosed so 50 that the mechanism, as well as the operator is protected, and yet ready access may be had to any of the driving parts for inspection or repair by removal of the various covers, and the parts themselves may be 55 readily detached for repair or replacement. The motor when in place is permanently connected with the operating parts of the machine so that all the operator need do to start or stop the operation of the machine is 60 to turn the switch in the electrical circuit. The motor does not interfere in any way with the operation of the machine by hand, but merely acts to lend additional momentum 65 to the fly wheel when the machine is so operated.

It should also be noted that the ratchet mechanism for feeding the meat support 15 is all mounted upon the reciprocating table 14 and has no connection with the base frame 10. This arrangement leaves the side of the 70 frame opposite the rotary knife 38 free to support the power drive. With ratchet drives previously in use this has been impossible for the reason that some form of stop mechanism supported upon the side of the 75 base frame has been necessary for the operation of the ratchet feed.

We claim:—

1. The combination with a slicing machine having a base frame, of a motor for 80 driving said machine, an opening in said frame for receiving said motor, means for securing said motor in said opening, and a removable cover for said motor secured to said base frame.

2. In combination, a slicing machine having a rotary slicing knife, a fly wheel operatively connected with said knife to rotate simultaneously therewith, a pulley for driving said knife and fly wheel, a motor for 90 operating said pulley, and a flexible belt connection between said motor and said pulley.

3. In combination, a slicing machine having a rotary slicing knife, a rectangular base 95 frame for said machine adjacent one side of which said knife is mounted, and power mechanism for driving said slicing knife mounted upon said base frame at the side thereof opposite said slicing knife.

4. In combination, a slicing machine having a rotary slicing knife, a rectangular base frame, a table mounted to reciprocate upon said base frame, mechanism carried by said table and free from said base frame for feeding material along said table, and power mechanism for said slicing machine mounted upon said base frame at the side thereof opposite said slicing knife.

5. In a slicing machine, a base frame, a work supporting table mounted to reciprocate upon said base frame, mechanism for feeding material upon said table, said mechanism being carried by said table above said base frame, and power mechanism for driving said slicing machine mounted on one of the sides of said base frame extending in the direction of movement of said work supporting table upon said base frame.

6. In a slicing machine, a rectangular base frame, a rotary slicing knife mounted on said base frame adjacent one side thereof, a fly wheel mounted on said base frame adjacent one end thereof, power mechanism for driving said slicing machine mounted on 120 said base frame at the side thereof opposite said slicing knife, a work support carried by said base frame and arranged to reciprocate thereon, and mechanism carried by 125 said work support above said base frame 130

- for feeding material upon said work support.
7. In a slicing machine, a base frame, a rotary slicing knife mounted on said base frame adjacent one side thereof, a motor carried by said frame at the side thereof opposite said slicing knife, gearing for connecting said motor with said slicing knife, a hand wheel for driving said slicing knife operatively connected with said knife and motor to rotate in unison therewith, a reciprocating table mounted on said base frame, a crank and connecting rod for reciprocating said table, ratchet mechanism for feeding material upon said table, and means for operating said ratchet mechanism from said crank and connecting rod.
8. In a slicing machine, a base frame having a horizontal web and an upright side web having an opening therein, a motor positioned in said opening, a band extending beneath said motor and supported by said horizontal web for securing said motor in place, and means for adjusting the length of said band to release said motor to permit removal thereof.
9. In a slicing machine, a frame comprising an upright web at one side thereof having an opening therein, a motor for driving said slicing machine, means for securing said motor within said opening, a cover for said motor, means for detachably securing said cover to said frame, electrical conductors for said motor, and a terminal for said conductors carried by said cover.
10. In a slicing machine, a base frame having an upright web forming a side wall therefor, a motor detachably carried by said side wall, gearing mounted on said side wall at a point removed from said motor, a casing for said motor detachably secured to said side wall, a casing for said gearing detachably secured to said side wall, a belt drive connecting said motor and gearing, and a removable guard for said belt secured to said motor casing and said gear casing.
11. In a slicing machine, a base frame having an upright side wall provided with an opening therethrough, a shaft extending through said opening for driving said slicing machine, a bearing member for said shaft detachably secured to said side wall, speed reduction gearing mounted on said bearing member for driving said shaft, a casing for said gearing removably carried by said side wall, a motor removably mounted in a second opening in said side wall, a cover for said motor removably secured to said side wall, conductors for said motor, a terminal for said conductors mounted on said cover, and a driving connection be-
- tween said motor and said speed reduction gearing.
12. A slicing machine comprising a base frame, a drive shaft journaled in said base frame, a gear secured to said shaft, a slicing knife, a pinion operated by said gear for driving said slicing knife, a fly wheel, a second pinion meshing with said gear for connecting said gear with said fly wheel, a motor for driving said slicing machine, and a third pinion meshing with said gear for operatively connecting said motor with said gear.
13. In a slicing machine, a base frame comprising an upper horizontal web and side webs extending downwardly at the edges of said horizontal web, a bearing extending downwardly from said upper web, a vertical stud shaft journaled in said bearing, a gear secured to the lower end of said stud shaft, a slicing knife mounted adjacent one side of said base frame, a pinion meshing with said gear for driving said slicing knife, a fly wheel journaled on said base frame adjacent one of the sides thereof extending at right angles to the side adjacent which said slicing knife is mounted, a motor carried by the side of said base frame opposite that adjacent which said slicing knife is mounted, pinions meshing with said gear for connecting said fly wheel and said motor with said gear, a work support mounted to reciprocate above said base frame, a crank secured to the upper end of said stud shaft for operating said work support, and mechanism having driving connection with said crank for feeding material upon said work support.
14. In a slicing machine, a slicing knife, a table for feeding material to said knife, a member for driving said knife and table, a fly wheel for said machine connected with said driving member, a motor for driving said machine, and gearing for connecting said motor with said driving member independently of the connection between said fly wheel and said member.
15. In a slicing machine, a frame plate, a gear mounted on said plate, a pinion meshing with said gear, slicing mechanism mounted on said plate and operated by said pinion, a second pinion meshing with said gear, and a motor mounted on said plate and operatively connected with said last-named pinion for driving said gear and slicing mechanism.

In testimony whereof we have signed our names to this specification on this 29th day of May, A. D. 1918.

AUGUST R. LUSCHKA.
JOSEPH FOLK.
